UNITED STATES PATENT OFFICE.

SEBASTIAN KARRER, OF URBANA, ILLINOIS, AND HUGH M. FRAMPTON, OF BALTIMORE,
MARYLAND.

PAPER SLIPPER.

Application filed July 20, 1923. Serial No. 652,689.

To all whom it may concern:

Be it known that we, SEBASTIAN KARRER and HUGH M. FRAMPTON, citizens of the United States, residing at Urbana, Illinois, and 3821 Ashburton Ave., Baltimore, Maryland, respectively, have invented certain new and useful Improvements in Paper Slippers, of which the following is a specification.

This invention relates to new and useful improvements in slippers generally, but more specifically to a slipper which is formed from a blank of sheet material.

The principal object of our invention is to provide a slipper which may be folded into compact form and which will consequently occupy but little space. Such slippers can be carried in a suit-case for ready use when travelling, occupying but little space therein, and avoiding the necessity of carrying the ordinary non-foldable slippers. Other uses for such slippers are readily apparent, such as, use by hotel guests, retail shoe store customers, etc.

Another object of our invention is to provide a foldable slipper of average size with yieldable fastening means whereby the slipper will automatically fit feet of different sizes.

A further object of our invention is to provide a foldable slipper which is extremely simple in construction and consequently cheap to manufacture.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:

Fig. 1 is a plan view of the slipper showing the same in its folded or compact relation.

Fig. 2 is a plan view showing the side portions elevated and in a position to receive the foot.

Fig. 3 is a plan view of the blank, and

Fig. 4 is a cross-sectional view taken on the line 4-4 of Fig. 2.

Similar reference characters designate corresponding parts throughout the several figures of the drawings.

Referring to the accompanying drawings,

we construct our slipper from a single blank of sheet material such as paper, fiberoid, etc. This blank is so constructed that it may be folded into a flat compact form. The blank is scored so as to provide a sole portion and two side portions which are connected to the opposite sides of the sole portion. In the form illustrated, the toe portions of the side portions and also the heel portions of the side portions are not connected. The side portions are connected by fastening means preferably elastic whereby a slipper of average size will readily conform to feet of different sizes. The fastening means is preferably located adjacent the toe portions of the sides and consequently the heel portions of the sides are caused to yieldably grip the heel of the user and thereby assist in retaining the slipper on the foot.

Specifically, our slipper is formed from a rectangular blank A of sheet material such as relatively stiff paper and it is scored substantially longitudinally along the lines 5-5 to form a centrally disposed sole portion 6 and two side portions 7-7, the latter being connected to the sole portion along opposite sides thereof. The scoring lines 5-5 preferably diverge from the heel portion 8 of the sole to the toe portion 9 thereof so as to conform substantially to the outlines of the human foot. It will be noted that the side portions 7-7 are substantially co-extensive in length with the sole portion 6.

The side portions 7-7 are held together by a fastening means which we have indicated as a whole by the reference numeral 10. Specifically this fastening means consists of a pair of buttons 11-11 respectively secured to the side portions 7-7 adjacent the toe end thereof, and a yieldable fastening means 12 such as an elastic band for instance, connects the buttons 11. We do not care to limit our invention to the use of yieldable fastening means, as non-elastic cords may be employed if so desired.

The heel portions of the side portions 7-7 are respectively cut away at 13-13, the line of cut being inclined from a point adjacent the sole portion 6. This cut away or beveled portion is located adjacent the narrow or heel portion 8 of the sole 6 and consequently this reduces the width of the heel end of each side portion so as to permit the latter to be folded over onto the sole portion. 110

Furthermore, these cut away or beveled portions 13 cooperate with the sole portion to form an inlet for the foot as is clearly shown in Fig. 2 of the drawings.

5 The toe portions of the side portions 7—7 and the sole portion 9 of the sole portion are respectively and conjointly formed with substantially V-shaped incisions 14—14 which form on the side portions 7—7 resultant yieldable toe engaging portions 15—15. The side portions 7—7 are respectively disposed in overlapping relation against the sole portion 6 as shown in Fig. 1. In this compact form the slipper may be 10 readily carried in suit-cases or the like and will occupy but very little space. The slipper is ready for instant use as all that is necessary to be done is to elevate the side portions 7—7 to the position shown 15 in Figure 2. The yieldable fastening means 10 retain the side portions in abutting relation so as to permit the foot to be readily inserted from the heel end of the slipper. After the foot is placed within the slipper, 20 the heel end portions of the side portions will be caused to frictionally engage the foot adjacent the ankle, and the toe engaging portions 15—15 of said side portions will 25 yieldably engage the toes of the foot. The elastic fastening means 10 permit the slipper 30 to automatically adapt itself to feet of different sizes within reasonable limits.

Without further description it is thought 35 that the many features and advantages of the invention will be readily apparent and it will, of course, be understood that changes in the form, proportion and minor details of construction may be resorted to without departing from the spirit of the invention 40 or scope of the appended claims.

We claim:

1. A foldable slipper comprising a single 45 blank of sheet material folded longitudinally along straight lines to form a resultant sole portion and two side portions respectively connected to the opposite sides of said sole portion, the entire side portions being foldable over flat on the original lines of fold one on the other and against the sole portion.

2. A foldable slipper comprising a single blank of sheet material folded longitudinally to form a resultant sole portion and two side portions respectively connected to the opposite sides of said sole portion and being substantially co-extensive therewith, and releasable means fastening the toe portions of the side portions in overlapping relation, the heel portions of said side portions being separated to permit the insertion of a foot, the entire side portions being foldable over flat on the original lines of fold one on the other and against the sole portion subsequent to the release of said fastening means. 55

3. A foldable slipper formed from a single blank of sheet material folded to form a resultant sole portion and two side portions respectively connected to the opposite sides of said sole portion, and yieldable fastening means connecting said side portions. 65

4. A foldable slipper formed from a single blank of sheet material folded to form a resultant sole portion and two side portions, the lines of folds diverging from the heel to the toe, the heel portion of said blank 75 being formed with forwardly extending incisions terminating at the respective folds to form resultant yieldable heel-gripping portions.

5. A foldable slipper formed from a single blank of sheet material folded to form a resultant sole portion and two side portions, the lines of folds diverging from the heel portion to the toe portion, and yieldable fastening means connecting said side portions. 80

6. A foldable slipper formed from a single blank of sheet material folded to form a resultant sole portion and two side portions, the lines of folds diverging from the heel portion to the toe portion, the heel end portions of the side portions being respectively beveled upwardly and forwardly from points adjacent the folds to form an inlet for the foot, and yieldable fastening 95 means connecting said side portions.

In testimony whereof we hereunto affix our signatures.

SEBASTIAN KARRER.
HUGH M. FRAMPTON.
